UNITED STATES PATENT OFFICE.

SVEN SWANSON AND SIGURD N. HOLMES, OF CHICAGO, ILLINOIS, ASSIGNEES OF ONE-
THIRD TO CHARLES E. HOLM, OF CHICAGO, ILLINOIS.

RAIL-FASTENING DEVICE.

1,182,814.

Specification of Letters Patent.

Patented May 9, 1916.

Application filed January 8, 1916. Serial No. 71,012.

To all whom it may concern:

Be it known that we, SVEN SWANSON, a subject of the King of Sweden, and SIGURD N. HOLMES, a citizen of the United States, 5 residing at Chicago, in the county of Cook and State of Illinois, have invented certain new and useful Improvements in Rail-Fastening Devices, of which the following is a specification.

10 The present invention appertains to fastening devices for rails and consists primarily in the combination with a chair having a rail engaging element at one side and a relatively movable element at the other 15 side for clamping the rail disposed between said elements, of means coacting with the last mentioned element to actuate the same to cause clamping action and at the same time secure this rail engaging element from 20 displacement by coöperation with the chair and the tie upon which the latter rests.

For a full understanding of the present invention, reference is to be had to the following description and the accompanying 25 drawings, in which:

Figure 1 is a transverse sectional view through a device forming the embodiment of this invention. Fig. 2 is an enlarged perspective view of the fastening member for 30 the movable clamping element. Fig. 3 is an enlarged perspective view showing the clamping element more clearly. Fig. 4 is a perspective view of one type of rail chair of which this invention consists. Fig. 5 is a 35 perspective view showing the type of chair designed for coöperating with the main track and guard rails. Fig. 6 is a slightly different type of chair that may be employed within the scope of this invention. Fig. 7 40 is a perspective view of the simplified form of chair.

Throughout the following detail description and on the several figures of the drawings, similar parts are referred to by like 45 reference characters.

In premising the description of this invention it may be mentioned that the rail chair which forms the subject-matter thereof may be made in either of two ways, first 50 by the process of casting where it takes the form shown in Figs. 1 and 4, and second by the rolling and punching process where it assumes the form shown in one or another of the Figs. 5, 6 and 7. So far as the scope

of the invention is concerned it is to be understood that the same is not to be confined to either one or the other of these constructions inasmuch as it is merely a matter of consideration from the manufacturing standpoint and does not affect either the utility 55 or the operation of the device.

Referring to Figs. 1 and 4, it will be observed that the invention comprises a chair consisting of the plate 1 which is of sufficient width to receive the rail 2 thereupon and 60 with which the upstanding rail engaging member 3 formed at one side of the chair engages. This element 2 is preferably cast in this construction integral with the base plate 1 of the chair and fits snugly against 65 the ball of the rail at the top portion thereof and against the base of the rail at the lower portion. Spaced from this member 3 the base plate 1 of the chair is formed with an aperture 4 in which is adapted to be received 70 the coacting rail engaging member 5 most clearly shown in Fig. 3. This member corresponds substantially in construction and 75 form to the member 3 but is, of course, movable so as to obtain a proper clamping action. The member 5, however, is provided 80 with a longitudinal groove 6 adjacent to its base in which is received one side of the base of the rail. At the end of the movable clamping member 5 it is formed with a vertical 85 groove or slot 7 merging into a head receiving seat 8 in its upper surface.

Another peculiarity of its construction is incidental to the inclination of the face 9 at the end of the member 5, the function of 90 which will be more clearly set forth hereinafter. Upon seating the element 5 in the recess 4 it is designed to be actuated into clamping position by means of a specially formed fastening member shown most 95 clearly in Fig. 2 of the drawing. This member takes the form substantially of a spike having the lateral head or lip 10 and the shank 11. This shank, however, at its upper portion is provided with lateral wedge-shaped wings 12, the rear surfaces of which coincide with the surface of the shank 11. It will be observed also that intermediate 100 this surface there is provided a plurality of serrations 13.

The fastening member described is designed to be inserted into place with the shank 11 interlocked in the groove 7 of

the clamping member 5 and upon driving said member downwardly into the rail tie 14 on which the chair is seated the lateral wings 12 coact with the inclined end face 9 of said member 5 and the rear edge of the aperture 4 in the chair base causing the clamping member to move laterally into clamping engagement with the rail. When the spike member has been driven home its 10 lip or head 10 will be received in the seat 8 and the clamping member thereby held against displacement. The serrations 13 on the rear face of the spike coact with the edge of the aperture 4 and the tie to prevent 15 likelihood of the spike working out of its position.

In Fig. 7 is shown a simplified form of chair which is constructed by rolling the sheet of metal in a well known manner and 20 upsetting from its body the upstanding rail engaging member 3^a which coacts with the rail as clearly described in respect to the element 3 mentioned in the previous description. The base plate is formed also 25 with a transverse rib 1^a in the rolling process and is designed to strengthen the base plate where the strain is greatest.

In Fig. 5 this same form of construction is further carried out in that the base plate 30 is provided with a pair of upstanding members 3^b to engage the main track rail seated upon said base plate. At a sufficient distance from these members 3^b the aperture 4^a is provided to enable the disposition of 35 a guard rail 2^a at one side of the main track rail, the chair thus forming a common fastening means for the two rails.

In Fig. 6 is disclosed a slightly modified construction though still carrying out the 40 same idea. In this form the base plate is punched out to form opposite rail engaging members 3^c, between which the meeting ends of two rails are adapted to be received. Opposite these arms, the openings 4^c are 45 provided so as to enable the positioning of the movable clamping members 5 in proper place for coöperation with the rail at the opposite side of the integral elements 3^c.

Copies of this patent may be obtained for five cents each, by addressing the "Commissioner of Patents, Washington, D. C."

This type thus enables the joining of two rails together.

Having thus described the invention, what is claimed as new is:

1. In combination, a rail chair having an upstanding member coacting with the rail at one side and apertured at the other side 50 of the rail, a clamping member disposed in the aperture for engaging the rail at the side opposite the upstanding member, said clamping member having an end wall formed with a spike receiving groove, and 55 a spike having a shank seated in the groove and provided with wedge means engaging the end wall at one side and a wall of the aperture at the other side.

2. A rail chair comprising a body of sheet 60 material having a rail engaging member struck up from the body to coact with the rail at one side, said chair being formed with an aperture spaced from the engaging member, a movable rail engaging member 70 disposed in said aperture to engage the rail at the opposite side, said movable member having an inclined end wall formed with a spike receiving groove terminating in a head receiving seat, and a spike adapted 75 to be interposed between the movable member and a wall of the aperture with its shank in the groove and head in the seat aforesaid whereby to wedge the movable member into clamping position.

3. In combination, a rail chair having a rail engaging member at one side thereof, a movable clamping member arranged at the other side thereof, and means for actuating 80 said clamping member and anchoring it in 85 position, said means comprising a fastening member having its shank interlocked with the clamping member, said fastening member being formed with lateral wings 90 of wedge shaped construction adapted to coact with the end of the clamping member for actuating the same as aforesaid.

In testimony whereof we affix our signatures.

SVEN SWANSON.
SIGURD N. HOLMES.
